Primary Examiner — Marissa J. Cash*Assistant Examiner* — Earl B Elowsky(74) *Attorney, Agent, or Firm* — Ricky Lam(57) **CLAIM**

The ornamental design for an airbrush kit as shown and described.

DESCRIPTION

FIG. 1 is a front, top, and right perspective view of an airbrush kit showing my new design;

FIG. 2 is a front elevational view thereof;

FIG. 3 is a rear elevational view thereof;

FIG. 4 is a right side elevation view thereof;

FIG. 5 is a left side elevational view thereof;

FIG. 6 is a top plan view thereof;

FIG. 7 is a bottom plan view thereof;

FIG. 8 is a rear, bottom, and left perspective view thereof; and,

FIG. 9 is an exploded perspective thereof.

The broken lines in the drawings depict portions of the airbrush kit that form no part of the claimed design.
